UNITED STATES PATENT OFFICE.

ARTHUR S. DUNKLE, OF BALTIMORE, MARYLAND, AND GEORGE E. HARNER, OF HOLTWOOD, PENNSYLVANIA.

CONCRETE RAIL-TIE.

1,115,416.

specification of Letters Patent. Patented Oct. 27, 1914.

Application filed March 14, 1914. Serial No. 824,797

To all whom it may concern:

Be it known that we, (1) ARTHUR S. DUNKLE and (2) GEORGE E. HARNER, citizens of the United States, residing at (1) 5 Baltimore, State of Maryland, and (2) Holtwood in the county of Lancaster and State of Pennsylvania, have invented certain new and useful Improvements in Concrete Rail-Ties; and we do hereby declare 10 the following to be a full, clear, and exact description of the invention, such as will enable others skilled in the art to which it appertains to make and use the same.

This invention relates to concrete rail ties, 15 and one of the principal objects of the invention is to provide a reinforced concrete tie which will yield to the action of the rolling stock as it passes over the rails, and which will be provided with expansion bolts 20 for securing the base flanges of the rails in place upon the tie, and which will be provided with a wooden core to absorb the shock and at the same time to render the 25 passing of the rolling stock over the rails practically noiseless.

Another object of the invention is to provide a concrete rail tie which can be quickly laid and the rails can be readily assembled, and in which the hollow tie is provided with 30 reinforcements extending lengthwise of the tie and provided with a wooden core which will absorb shocks and act as a quietus.

These and other objects may be attained by means of the construction illustrated in 35 the accompanying drawings, in which,

Figure 1 is a side elevation of a concrete tie made in accordance with this invention the rails being shown in section, Fig. 2 is a 40 top plan view of one end of the tie taken on the line 2—2 of Fig. 1, Fig. 3 is a detail sectional view taken on the line 3—3 of Fig. 2, Fig. 4 is a vertical sectional view taken on the line 4—4 of Fig. 1, Fig. 5 is a similar 45 section taken on the line 5—5 of Fig. 1, Fig. 6 is a horizontal sectional view of the end portion of the tie taken on the line 6—6 of Fig. 1, and Fig. 7 is a plan view of the various 50 reinforcing wires used to give strength to the tie, said wires being embedded within the concrete during the manufacture of the tie.

Referring to the drawing, the numeral 1 55 designates the main body portion of the concrete tie, and embedded within the concrete at the time the same is molded into the form

of a tie are the reinforced rods 2 near the bottom of the tie, said reinforced rods each having a hook 3 at its opposite ends, and an inclined portion 4. The reinforcing rods 5 are also embedded within the concrete, said 60 rods being provided with inwardly-bent ends 6, and the inclined portions 4 converge at the ends of the tie and the hooks 3 engage the ends 6 of the reinforcing rods 5, as shown more clearly in Fig. 6.

Extending longitudinally of the tie is a flaring recess 7, and placed within the recess 7 is a wooden core 8, said core being placed in position after the tie has been molded, and said core serving to give resiliency and 70 absorb shocks and also to serve to deaden the noise of the rolling stock passing over the rails.

The top or cover portion of the tie 9 is provided with a tapering rib 10 which extends throughout the length and breadth of the recess 7. Reinforcing members or rods 11 extend through the rib 10 and at their ends said reinforcing rods 11 are provided with inclined portions 12 and converging 80 portions 13 which terminate in hooks 14. The reinforcing rods 15 extend through the upper portion of the tie and said rods are provided with curved ends 16 and outwardly extending hooks 17 at their ends.

Formed integral with the upper portion 9 of the tie are the rail engaging members 18, and the hooks 14 and 17 of the reinforcements 15 and 11 are connected within the members 18 by a cross bar *a* and are 90 embedded during the molding of the tie. The member 18 is provided with a recess 19 which conforms to the contour of the base flange 20 of the rail 21, and a metal flange engaging element 22 is secured to the tie 95 and overlaps the base flange of the rail as shown in Fig. 1. The metal flange engaging element 22 is secured to the tie by means of an expansion bolt comprising a slit tube 23 and a bolt 24 engaging the interior screw 100 threads of said tube or sleeve.

A centrally disposed expansion bolt 25 comprises a similar slit sleeve or tube and a bolt 26 engaging the interior screw threads thereof. A spiral spring 27 surrounds the 105 shank of the bolt 26 and bears at one end against the under side of the wrench engaging head of the bolt, while the opposite end of the spring bears against the upper end of the slit sleeve 25.

From the foregoing it will be obvious that a rail tie made in accordance with this invention will be very strong and durable, will outlast wooden ties many times over, will 5 slightly yield to the weight of the rolling stock, and will be practically noiseless in operation, while the cost of manufacture is comparatively slight.

Various changes in the details of construction 10 may be resorted to without departing from the spirit and scope of the invention as defined in the claims.

What is claimed is:—

1. A concrete rail tie comprising two members one of which is provided with a flaring recess, and the other with a tapering rib to fit said recess, reinforcing rods extending lengthwise and crosswise of the tie.
- 20 2. A concrete rail tie comprising two members one of which is provided with a tapering recess extending longitudinally thereof, and the other member being provided with a rib to fit said recess, a wooden core 25 loosely placed in the bottom of said recess, and reinforcing rods extending longitudinally of the two members of the tie, said reinforcing rods having inclined and converging ends provided with hooks to engage the inwardly extending members of the other reinforcing rod, and said two members of the tie being connected together by expansion bolts.

3. A concrete rail tie comprising two members having an intermediate wooden core, and reinforcing rods extending lengthwise of said tie, an integral engaging element for the base flange of a rail, and a metal lug for engaging the opposite flange of the rail, said lug being secured to the tie by an expansion bolt.

4. A concrete tie comprising two longitudinal sections, one of which is provided with a flaring recess and the other with a rib to fit said recess, an intermediate wooden core adapted to absorb the noises of the rolling stock, and to serve as a base for said tie, reinforcing rods extending through both sections of the tie, said rods having terminal hooks and inwardly bent ends, interlocked in the concrete, lugs at the ends of the tie for engaging the base flanges of the rail, metal engaging elements for the inner flanges of the rails, expansion bolts for holding said elements in place, and a centrally disposed expansion bolt extending through both members of the tie and through the wooden core.

In testimony whereof we affix our signatures in presence of two witnesses.

ARTHUR S. DUNKLE,
GEORGE E. HARNER.
